US00D613293S

(12) **United States Design Patent**
Sheba

(10) **Patent No.:** **US D613,293 S**
(45) **Date of Patent:** **** Apr. 6, 2010**

(54) **MEMORY CARD HOLDER**

(75) Inventor: **Yaron Sheba**, Mountain View, CA (US)

(73) Assignee: **SanDisk Corporation**, Milpitas, CA (US)

(**) Term: **14 Years**

(21) Appl. No.: **29/310,553**

(22) Filed: **Aug. 26, 2008**

(51) **LOC (9) Cl. 14-02**

(52) **U.S. Cl. D14/435; D3/247**

(58) **Field of Classification Search** D14/435, D14/436, 437, 438, 432, 356; D3/294, 273, D3/201, 203.5, 203.6, 284, 295, 903, 203.1, D3/203.2, 247, 249, 250, 227; D9/414, 422, D9/424, 430, 432, 415; D28/83, 77, 78; D6/632, 407, 634, 635, 627-629, 314; 206/38, 206/38.1, 39, 232, 804, 815, 308.1, 308.3, 206/472, 473, 483, 474, 477, 480, 569, 570, 206/482, 485, 486, 320, 305, 307, 307.1, 206/450, 701, 722, 387.1, 387.13, 491, 455, 206/316.1, 316.2, 706, 725, 312, 223, 235, 206/236, 811, 710, 454, 531, 493, 445, 311, 206/823, 581, 574, 37, 39.4, 39.5, 39.6, 39.1, 206/39.3, 776, 709, 449, 555; 206/807, 459.5, 206/556; 361/756, 686, 801, 802, 737, 752, 361/727; 150/147, 149, 150, 900, 131; 235/486, 235/487, 451, 492, 493, 380, 386, 382, 488; 242/378.2, 375, 385.1, 371, 400; 439/630, 439/945, 61, 135, 946; 53/471; 40/642.02, 40/655, 661.07, 765, 1.5, 427, 777, 649, 40/1.6, 666, 661.04, 27.5, 653, 308; 224/277, 224/929, 162, 269, 191, 254, 255, 274, 245, 224/196; 220/4.22, 526, 281, 315, 326, 826, 220/263, 835, 324, 838, 4.23, 839; 16/361; 215/201; 211/40; 70/276, 58, 63; 190/109, 190/117, 901; 312/244; 402/3, 76; D7/629; D8/339, 330, 331, 343; 292/116, 137, 148, 292/156, 302, DIG. 11; 132/293-295, 298, 132/301, 300; D21/333, 54, 55, 57; D99/34; 24/3.11, 3.12; 403/348; D20/43; D19/78, D19/90, 1; 382/124; 356/71; 383/43, 106; 283/904; 281/42; D11/78.1; 174/353, 372, 174/386, 535; 109/23, 24; 340/568.7

CLAIM

The ornamental design for a memory card holder, as shown and described.

DESCRIPTION

FIG. 1 is a perspective view of a memory card holder that incorporates my new design.

FIG. 2 is a front view thereof.

FIG. 3 is a rear view thereof.

FIG. 4 is a right-side view thereof.

FIG. 5 is a left-side view thereof; and,

FIG. 6 is a top view thereof.

The bottom view thereof is identical to the top view thereof shown in FIG. 6.

1 Claim, 4 Drawing Sheets
